UNITED STATES PATENT OFFICE.

XAVIER J. JOLLER, OF CHICAGO, ILLINOIS.

CIGAR-HOLDER.

1,189,962.

Specification of Letters Patent.

Patented July 4, 1916.

Application filed November 3, 1913. Serial No. 798,897.

To all whom it may concern:

Be it known that I, XAVIER J. JOLLER, a citizen of the United States, and a resident of the city of Chicago, county of Cook, and State of Illinois, have invented certain new and useful Improvements in Cigar-Holders, of which the following is a specification.

My invention relates to cigar holders and the object of this improvement is to provide a device of this character which will hold a lighted cigar in the pocket of a smoker without danger of igniting his clothing.

Other objects will appear hereinafter.

The invention consists in the combinations and arrangements of parts hereinafter described and claimed.

The invention will be best understood by reference to the accompanying drawing forming a part of this specification, and in which,

Figure 1 is a side view of a cigar holder embodying my invention, Fig. 2 is a longitudinal section of the same, and Figs. 3 and 4 are enlarged sections taken on lines 3—3 and 4—4 respectively of Fig. 1.

The preferred form of construction, as illustrated in the accompanying drawing comprises a tubular casing 5 having its upper end open. Cut out and struck up from the side of casing 5 is a spring clip 6 adapted to engage the pocket of a smoker to lock the device in his pocket. The hole 7 from which the spring clip 6 is cut out provides a means for air entering the casing 5 to remove tobacco odors from such casing. Perforations 8 are also provided in casing 5 directly opposite opening 7 for the same purpose. At the upper edge of casing 5 is provided a notch 9 and a handle 10 is provided with an outwardly bent end portion 11 engaging notch 9. The lower end of handle 10 is secured by means of solder or its equivalent to an ash tray 12. The handle 10 is of a length to maintain the ash tray 12 at the bottom of casing 5 when bent end portion 11 is in notch 9. A guide member 13 is struck up from casing 5 and engaged around handle 10 to prevent lateral movement of the handle 10 after it has been moved upwardly and the bent end portion 11 disengaged from the notch 9 of casing 5.

Hinged to the top of casing 5 is a cap 14. Through the axial center of cap 14 is a needle 15 with its point extending downwardly to slightly above the lower edge of cap 14 so that there will be no danger of

the point of said needle scratching a person when the cap is open. A compression spring 16 is provided in cap 14 on needle 15 to normally hold it at its upper terminal of movement. On the inner side of cap 14 is provided a conical shaped cup 17 adapted to fit the small end of a cigar, the needle 15 extending entirely through the cup 17. In use the small end of a cigar may be pressed into cup 17 thereby perforating such small end of the cigar with the needle 15, or the cigar may be placed in casing 5 and the cap 14 opened until the needle 15 is substantially perpendicular to the axis of casing 5 and the needle 15 pressed until it perforates the end of the cigar laterally. A finger piece 18 is provided on cap 14 to facilitate operating needle 15.

With the use of a cigar holder of the character described a smoker may place the cigar in casing 5 and close cap 14 and place the device in his pocket without fear of setting his clothing on fire. When he desires to use the cigar again he opens cap 14, and by the aid of the bent end 11 of handle 10, moves the ash tray 12 upwardly in casing 5 until the cigar is removed from casing 5. The ash tray 12 collects any ashes that may remain on the cigar and prevents the same from remaining in the lower end of casing 5.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the kind described comprising a tubular casing open at one end; a cap on the open end of said casing; an ash tray in said casing at the lower end thereof; and a handle on said ash tray and engaging said cap preventing movement of said ash tray, substantially as described.

2. A device of the kind described comprising a tubular casing open at one end; a cap on the open end of said casing; an ash tray in said casing at the lower end thereof; a handle on said ash tray and engaging said cap preventing movement of said ash tray;

- and a guide struck up from said casing and engaging said handle preventing lateral movement of the latter, substantially as described.
- 5 3. A device of the kind described comprising a tubular casing open at one end and a notch therein adjacent said open end; a handle extending longitudinally in said casing with a bent end engaging said notch;
- 10 an ash tray at the lower end of said handle; and a cap on said open end engaging said handle maintaining the latter in said notch and said ash tray at the bottom of said casing, substantially as described.
- 15 4. A device of the kind described comprising a tubular casing open at one end and a notch therein adjacent said open end; a handle extending longitudinally in said casing with its upper end bent and extending laterally through said notch out of said casing; an ash tray at the lower end of said casing and secured to the lower end of said handle; a guide struck up from the wall of

said casing and engaging said handle; and a cap on said casing locking the bent end of 25 said handle in said notch, substantially as described.

5. A device of the kind described comprising a hollow casing open at one end; a tray slidably mounted in said casing; and a 30 handle for moving said tray in said casing, substantially as described.

6. A device of the kind described comprising a hollow casing open at one end; a tray slidably mounted in said casing; and a 35 handle on said tray extending outwardly to the opening in said casing, for moving said tray in said casing, substantially as described.

In testimony whereof I have signed my 40 name to this specification in the presence of two subscribing witnesses.

XAVIER J. JOLLER.
